UNITED STATES PATENT OFFICE.

FRANK B. RAE, OF CLEVELAND, OHIO.

TRANSMISSION MECHANISM.

1,153,338.

Specification of Letters Patent. Patented Sept. 14, 1915.

Application filed December 9, 1912. Serial No. 735,608.

To all whom it may concern:

Be it known that I, FRANK B. RAE, a citizen of the United States, residing at Cleveland, in the county of Cuyahoga and State of Ohio, have invented a certain new and useful Improvement in Transmission Mechanism, of which the following is a full, clear, and exact description.

This invention relates to a transmission mechanism by which power is transmitted from a driving to a driven shaft.

The object of the invention is to provide a device for effecting variation in the speed of the driven shaft from a substantially constant speed driving shaft, the transmission mechanism being so designed as to permit gradual and progressive change of speed, rather than abrupt changes by steps, as is the case where certain fixed assemblages of gears is employed.

The flexibility and ease of operation of my speed control will be apparent as the description proceeds.

Generally speaking, the invention comprises the elements and combinations thereof set forth in the accompanying claims.

Reference should be had to the accompanying drawings forming a part of this specification in which

Fig. 1 is a side elevation with certain portions in section of the transmission mechanism, and devices for effecting speed changes; Fig. 2 is a top plan view of portions of the mechanism for effecting the speed changes; Fig. 3 is a front elevation of one of the guiding devices for the annulus.

The mechanical principle upon which the device herein disclosed operates may be very simply illustrated by the movements of which a coin partakes as it is spun upon a flat surface,—more particularly when the motion of the coin is dying down and approaching a flat position on the surface upon which it is spun. Observing a coin spun as indicated, it will be noted that the coin itself has a vibratory or wobbling movement with respect to the table. That is to say, the coin apparently is wobbling upon its periphery, and this movement or vibration is quite rapid in rate. Observation will show that there is also a turning of the coin about its own central axis, but the speed of rotation about its axis is very much reduced from the speed of vibration of the coin to which reference has just been made.

In this invention, the annulus 1 may be likened to the coin. The disks 2 and 3 which are relatively fixed for any given inclination of the annulus, may represent the surface upon which the coin is vibrating, the two disks being used because the path of the wobbling disk is more definitely defined. The driven shaft 4 is secured to the annulus 1, at the central portion thereof. Under such conditions, if the disk 1 be caused to vibrate or wobble about its central axis, this vibration will result in a certain rotative movement of the annulus which will be transmitted to the shaft 4.

Having thus described the mechanical principle upon which this device operates, I may now speak a little more definitely of the construction herein shown as being one embodiment of my invention. The driving shaft is indicated at 5, and upon this shaft there is secured a fixed sleeve 6, and back of this there is another sleeve 7 encircling the shaft, the last mentioned sleeve being movable longitudinally of the shaft, but being so mounted as to partake of the rotative movement of the driving shaft. Upon the sleeve 6 there are mounted two levers indicated at 8. These levers are pivotally secured upon the sleeve 6 by means of a pin 9. Upon the sleeve 7 there is journaled a pin 10, upon the opposite ends of which there are pivotally secured levers 11.

To the annulus there is axially secured a short shaft 12, and upon this shaft there is mounted a sleeve 13, which may freely move along the shaft. There is also associated with the driving shaft 5, a sleeve 14 which is free to move along this shaft and does not rotate with it. This sleeve is adapted to be moved by any suitable mechanism, and for the purpose I have shown a lever 15 pivoted at its lower end upon a standard 16. This lever has pivotal engagement with the sleeve 14 to cause movement of the sleeve as the lever is moved. This lever may be equipped with a pawl 17 which may be operated by the lever 18. The pawl may be associated with a notched rack 19, so that the lever may be held in adjusted position. The movement of the lever 15 will cause movement of the sleeves 14 and 7, thereby causing the shaft 12 to assume different degrees of angularity with respect to the vertical.

The disk 2 may conveniently be mounted upon a fixed standard 20, while the disk 3

may be carried by a standard 21, which is movable, so that the disks 2 and 3 may automatically assume proper position with respect to each other and to the annulus 1, as the degree of angularity of the annulus 1 is changed.

For automatically causing the shifting of the disk 3, the proper amount, I have provided springs 22 which are suitably housed 10 in a casing 23, and bear against the reverse side of the disk 3. It will be understood that the relative position of the disks 2 and 3 is fixed for any given position of the annulus 1. The adjustability of the disks is 15 provided to permit and accommodate a variety of positions of the annulus 1.

The lower portion of the standard 21 may be slotted to engage with a pin 21^a which will limit the movements of the standard.

20 The connection between the annulus 1 and the shaft 4 is by means of a universal joint generally indicated at 24. This universal joint may be of any desired type, and no special claim to it is here made.

25 The disks 2 and 3 with which the annulus 1 coöperates may be constructed in any desired or appropriate manner. I would, however, recommend that the particular portions of the disks 2 and 3 with which the 30 annulus coöperates, should be made of material which will have a good friction surface, so that there will be a minimum of slipping between the annulus and the surface with which it coöperates. I have in 35 the drawing therefore shown the disks 2 and 3 as provided with inserted portions 2^a and 3^a which may be made of such material as fiber or other good frictioning material.

It will be understood that in the assemblage of elements as shown in the drawing, 40 if the lever 15 be pushed toward the right to the position indicated at 15^a, the connecting levers 8 and 11 will assume a substantially horizontal position, at which time, the 45 shaft 12 is in line with the driving shaft 5. When, however, the lever 15 is in the position shown in full lines in Fig. 1, the shaft 12 is at an angle with respect to the shaft 5. The lower end of the shaft 12 being substantially upon the axis of the shaft 5, portions 50 of the shaft 12 are therefore bodily rotated about the axis of the shaft 5, as the last mentioned shaft is rotated, the movement of the shaft 12 generating a conical surface. The annulus 1 will partake of the 55 movement of the shaft 12, and will wobble or vibrate between the disks 2 and 3, and as heretofore explained, this movement will produce a slight rotative movement of the annulus 1, which will be imparted to the shaft 4.

Difference of angularity of the annulus 1 will produce various speed relationships between the driving and driven shafts. The 60 speed of the shaft 4 with respect to the con-

stant speed of the shaft 5 may be increased as the angularity of the annulus 1 is increased, and conversely the speed of shaft 4 is decreased as the annulus 1 approaches near a vertical position, and when the annulus is in a vertical position, the shaft 4 does not turn at all; because under such conditions, there is no movement of the annulus 1.

It will be obvious that modifications may 75 be made in the particular assemblage of elements which I have shown, and I therefore do not confine myself, except as the phraseology of the claims may so limit.

Having thus described my invention, what 80 I claim is:

1. The combination with a driving shaft, and a driven shaft, of an annulus flexibly connected at its central portion to the driven shaft and having its center in line with the 85 driving shaft, operative connections between the driving shaft and the annulus for wabbling and turning the annulus about its central axis as the driving shaft is turned.

2. The combination with a driving shaft 90 and a driven shaft of an annulus mounted to have its center in line with the driving and driven shaft, operative connections between the annulus and the driven shaft, guiding means with which the annulus co- 95 operates, and operative connections between the annulus and the driving shaft whereby the annulus may be wobbled and turned about its center.

3. The combination with a driving shaft 100 and a driven shaft, of an annulus flexibly mounted at its central portion to the driven shaft and having its center in line with the driving shaft, operative connections between the driving shaft and the annulus for wabbling and turning the annulus about its central axis as the driving shaft is turned, said operative connections being adjustable to vary the degree of wabbling and rotation of the annulus.

4. The combination with a driving shaft and a driven shaft, of an inclined annulus, the center of the annulus being in line with the driving and driven shafts, spaced guiding disks with which the said annulus co- 110 operates, operative connections between the annulus and the driven shaft, and operative connections between the annulus and the driving shaft, whereby the annulus is wabbed as the driving shaft is turned.

5. The combination with a driving shaft and a driven shaft, of an inclined annulus, guiding means with which said annulus co- 115 operates, the center of the annulus being in line with the driving and driven shafts, operative connections between the driven shaft and the annulus; a short shaft connected at right angles to the plane of the annulus, operative connections between the driving shaft, and the said short shaft, whereby the 120

- annulus is wabbled as the driving shaft is turned.
6. In combination with a driving shaft and a driven shaft, of an inclined annulus mounted to have its center in line with the center of the driving and driven shafts, guiding means with which the annulus cooperates, operative connections between the annulus and the driven shaft, operative connections between the annulus and the driving shaft, whereby the disk is wabbled as the driving shaft is turned, said connections being adjustable to vary the inclination of the said inclined annulus.
7. The combination with a driving shaft, and a driven shaft, of an inclined annulus mounted to have its center in line with the center of said shafts, guiding means coöperating with the annulus, operative connections between the driven shaft and the annulus, a short shaft secured to the central portion of the annulus and at right angles to the plane thereof, a sleeve upon the short shaft, a fixed sleeve upon the driving shaft, a movable sleeve upon the driving shaft, levers connecting the sleeves upon the driving shaft, with the sleeve upon the short shaft, means for varying the position of the movable sleeve upon the driving shaft, substantially as described.
- In testimony whereof, I hereunto affix my signature in the presence of two witnesses.

FRANK B. RAE.
